(57) **CLAIM**

The ornamental design for a mobile phone case, as shown and described.

DESCRIPTION

FIG. 1 is a front perspective view of a mobile phone case, showing our new design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof;

FIG. 7 is a bottom plan view thereof;

FIG. 8 is a rear perspective view thereof; and,

FIG. 9 is an exploded front perspective view of FIG. 1, shown with the two components of the mobile phone case separated for clarity of disclosure.

The dot-dash broken lines in FIG. 9 show the path along which the components of the case are separated. All other broken lines depict unclaimed environment. The broken lines form no part of the claimed design.
